WILLIAM REAVELL, OF IPSWICH, ENGLAND.

AIR-COMPRESSOR.

1,070,733.

Specification of Letters Patent.

Patented Aug. 19, 1913.

Application filed July 12, 1909. Serial No. 507,209.

To all whom it may concern:

Be it known that I, WILLIAM REAVELL, of Ipswich, in the county of Suffolk, England, have invented a certain new and useful Improvement in Air-Compressors, whereof the following is a specification, reference being had to the accompanying drawings.

My improvement is particularly applicable to a pump adapted to be directly connected with an electric motor in an apparatus designed for cleaning dynamos, transformers, switchboard instruments, etc., by means of an air blast, and, my improvement includes mechanical means for obtaining reciprocatory motion from the rotary motor armature shaft within a dust-proof casing containing the cylindrical pump chambers.

As hereinafter described my invention includes a rotary shaft which may be either directly or indirectly connected with the armature shaft; a pump plunger arranged to reciprocate at right angles to the axis of said shaft; and a slide block, operatively connecting said crank and plunger and mounted to reciprocate in said plunger at right angles to the latter. As hereinafter described said means for converting rotary motion into reciprocatory motion is embodied in two pumps, both double acting. However one is arranged for simple compression, but the other is arranged for two-stage compression.

My invention includes the various novel features of construction and arrangement hereinabove more definitely specified.

In the drawings:—Figure I is a longitudinal sectional view of a double acting pump embodying my invention and adapted for simple compression of air. Fig. II is a transverse sectional view taken on the line II, II in Fig. I. Fig. III is a longitudinal sectional view similar to Fig. I but showing a modified form of my invention adapted for two-stage compression of air.

Referring to the form of my invention shown in Figs. I and II; the casing 1 has the bearing 2 for the shaft 3, which may be directly connected with the armature shaft or as shown in Fig. II said shaft 3 may be provided with means detachably connecting it with the sprocket wheel 5, and thus adapted to be connected with the motor shaft by a chain. As shown in Fig. II; said shaft 3 is prevented from longitudinal displacement by the set screw 7, extending through said casing 1 and having its reduced end 8

fitted in the circumferential groove 9 on said shaft. The flange 10 on said shaft projecting within the opening 11 in the casing serves to return to the oil-chamber 13 any surplus lubricating oil which might otherwise be thrown out. The perforated band 14 which encircles said shaft 3 but depends in said chamber so as to dip below the oil-level 15 in the latter, serves to continuously lubricate said shaft. Said shaft 3 carries the crank 16 which is fitted in the cylindrical bearing 17 in the slide block 18, and, said block 18 is fitted to slide in the cylindrical bearing 19 in the reciprocating plunger 20, which as shown in Fig. I has its opposite ends fitted to reciprocate in the counterpart pump chambers 22 which are oppositely aligned in said casing 1. Each of said chambers 22 has a removable cover 25 containing the air inlet port 26 controlled by the ball valve 27 which is normally pressed by the spring 28 to close said port 26. Said valve 27 and spring 28 are carried by the removable screw threaded plug 29, which is fitted in the corresponding socket 30 in said cover 25. Said chamber 22 is provided with the outlet port 32, controlled by the ball valve 33 which is normally pressed by the spring 34 to close said port 32, which opens from said chamber 22 into the by-pass conduit 36, having the discharge outlet 37 for the compressed air, which is delivered from said chambers 22 in alternation. Said valve 33 and spring 34 are carried by a removable screw threaded plug 39 which is fitted to the corresponding socket 40 in said casing 1. In order to permit the escape of air from said conduit 36 under abnormal pressure, said plug 39 is provided with the safety vent 42, controlled by the ball valve 43 normally pressed by the spring 44 to close said vent; said ball 43 and spring 44 being carried by the removable screw threaded plug 45 fitted in the corresponding socket 46 in said plug 39. It is to be understood that by the rotation of said shaft 3 said plunger 20 is reciprocated in said pump chambers 22 so as to take air in one chamber through the port 26 leading thereto, and contemporaneously discharge compressed air through the outlet port 32 of the other chamber; the air thus alternately compressed in the respective chambers being delivered through the common outlet including said conduit 36 and outlet 37.

The form of my invention shown in Fig.

III includes the casing 51 which is constructed and arranged at the right hand end like the embodiment of my invention shown in Fig. I including an inlet valve 53 and outlet valve 54 for the pump chamber 55, constructed and arranged like the valves 27 and 33 above described. However, the conduit 56 conducts compressed air from said chamber 55 to the opposite pump chamber 57 and may be termed a by-pass conduit, from which the air compressed by two stages is finally discharged from the port 58 controlled by the ball valve 59 which is normally pressed by the spring 60 to close said port 58. Said valve 59 and spring 60 are carried by the removable screw threaded plug 61, which is fitted in the corresponding socket 62 in said casing 51. The compressed air discharged from said outlet 58 under control of the automatic valve 59 is directed through the discharge outlet 64 which may be manually controlled by the valve 65. It is to be understood that if the pump shown in Fig. III continues to operate when said valve 65 is closed, or said conduit 56 is otherwise charged with air at abnormal pressure, a safety vent for the same is afforded by the port 67 under control of the valve 68 which is similar to the valve 43 above described.

The form of my invention shown in Fig. III operates as follows:—The piston being moved toward the left hand side of Fig. III, air is admitted by the inlet valve 53. Assuming that the chamber 57 was filled with air at ordinary atmospheric pressure, said air is compressed into the clearance space at that end of the cylinder and into the conduit 56. Assuming that said clearance space represents 25% of the cylinder volume; the pressure of the air thus compressed would be raised to seventy-five pounds absolute. The piston then being moved toward the right hand side of Fig. III, the air which was aspirated at the valve 53 during the previous stroke is compressed while the air in the aforesaid clearance space of the chamber 57 and conduit 56 expands behind the receding piston until the pressure at opposite ends of said piston is equalized at twenty-five pounds absolute. Thereupon, the valve 54 opens and during the remainder of said stroke of the piston the compressed air in the chamber 55 is forced into the conduit 56 and chamber 57, and, at the completion of said stroke the air thus compressed is at a pressure of twenty-five pounds. Said piston being then moved toward the left hand side of Fig. III atmospheric air is again admitted at the valve 53 while the air in the chamber 57 and conduit 56 is further compressed; so that, on the next return stroke of the piston the pressures at the opposite ends of the cylinder must balance at a higher pressure, viz; thirty-

five pounds, and, such operation continues until a pressure is reached which is the desired delivery pressure capable of opening the valve 59. Assuming that said delivery pressure is one hundred and five pounds absolute, the volume of air delivered at that pressure would be; the volume swept by the piston multiplied by fifteen and divided by one hundred and five.

It may be observed that in both forms of my invention above described the slide blocks not only serve to operatively connect the rotary shaft with the reciprocating plunger but also serve to automatically lubricate the latter by dipping into and raising the oil in the casing.

I do not desire to limit myself to the precise details of construction and arrangement above described, as it is obvious that various modifications may be made therein without departing from the scope of the appended claims.

I claim:—

1. In an air compressor, the combination with a casing having cylindrical air chambers at respectively opposite ends thereof, a crank chamber between said air chambers, a conduit connecting said air chambers, and a discharge outlet from said conduit; of a cylindrical piston plunger of uniform diameter throughout its length, mounted to reciprocate in said casing and alternately compress the air in said chambers; means arranged to reciprocate said plunger comprising a cylindrical slide block mounted to reciprocate in said plunger transversely with respect to the plunger axis, a crank shaft extending transversely with respect to said plunger axis, and a crank on said shaft fitted in said slide block in said crank chamber; a spherical air inlet valve opening inward and controlling the admission of air to one of said chambers; a spherical air outlet valve opening outward and controlling the emission of air from the same chamber to said conduit; a spherical safety vent valve in concentric relation with said outlet valve controlling the escape of air from said conduit to the atmosphere, a spherical discharge valve opening outward and controlling the delivery of compressed air from said conduit; and, springs operatively connected with each of said valves, normally maintaining the same closed; whereby, a greater pressure is required to operate said vent valve than any of the other valves, and, a greater pressure is required to operate said discharge valve than said outlet valve, and, two stage compression is effected.

2. In an air compressor, the combination with a casing having cylindrical air chambers at respectively opposite ends thereof, a crank chamber between said air chambers, a conduit connecting said air chambers, and a discharge outlet from said conduit; of a cy-

cylindrical piston plunger of uniform diameter throughout its length, mounted to reciprocate in said casing and alternately compress the air in said chambers; means arranged to reciprocate said plunger comprising a cylindrical slide block mounted to reciprocate in said plunger transversely with respect to the plunger axis, a crank shaft extending transversely with respect to said plunger axis, and a crank on said shaft fitted in said slide block in said crank chamber; an automatic air inlet valve opening inward and controlling the admission of air to one of said chambers; an automatic air outlet valve opening outward and controlling the emission of air from the same chamber to said conduit; an automatic safety vent valve in concentric relation with said outlet valve controlling the escape of air from said conduit to the atmosphere; an automatic discharge valve opening outward and controlling the delivery of compressed air from said conduit; and, springs operatively connected with each of said valves, normally maintaining the same closed; whereby, a greater pressure is required to operate said vent valve than any of the other valves, and, a greater pressure is required to operate said discharge valve than said outlet valve, and, two stage compression is effected.

3. In an air compressor, the combination with a casing having cylindrical air chambers at respectively opposite ends thereof, a crank chamber between said air chambers, a conduit connecting said air chambers, and a discharge outlet from said conduit; of a cylindrical piston plunger of uniform diameter throughout its length, mounted to reciprocate in said casing and alternately compress the air in said chambers; means arranged to reciprocate said plunger comprising a cylindrical slide block mounted to reciprocate in said plunger transversely with respect to the plunger axis, a crank shaft extending transversely with respect to said plunger axis, and a crank on said shaft fitted in said slide block in said crank chamber; an automatic air inlet valve opening inward and controlling the admission of air to one of said chambers; an automatic air outlet valve opening outward and controlling the emission of air from the same chamber to said conduit; an automatic safety vent valve controlling the escape of air from said conduit to the atmosphere; an automatic discharge valve opening outward and controlling the delivery of compressed air from said conduit; and, springs operatively connected with each of said valves, normally maintaining the same closed; whereby, a greater pressure is required to operate said vent valve than any of the other valves, and, a greater pressure is required to operate said discharge valve than said outlet valve, and, two stage compression is effected.

4. In an air compressor, the combination with a casing having cylindrical air chambers at respectively opposite ends thereof, a crank chamber between said air chambers, a conduit connecting said air chambers, and a discharge outlet from said conduit; of a cylindrical piston plunger of uniform diameter throughout its length, mounted to reciprocate in said casing and alternately compress the air in said chambers; means arranged to reciprocate said plunger comprising a cylindrical slide block mounted to reciprocate in said plunger transversely with respect to the plunger axis, a crank shaft extending transversely with respect to said plunger axis, and a crank on said shaft fitted in said slide block in said crank chamber; an automatic air inlet valve opening inward and controlling the admission of air to one of said chambers; an automatic air outlet valve opening outward and controlling the emission of air from the same chamber to said conduit; an automatic discharge valve opening outward and controlling the delivery of compressed air from said conduit; and, springs operatively connected with each of said valves, normally maintaining the same closed; whereby, a greater pressure is required to operate said discharge valve than said outlet valve, and, two stage compression is effected.

5. In an air compressor, the combination with a casing having cylindrical air chambers at respectively opposite ends thereof, a crank chamber between said air chambers, a conduit connecting said air chambers, and a discharge outlet from said conduit; of a cylindrical piston mounted to reciprocate in said casing and alternately compress the air in said chambers; means arranged to reciprocate said piston comprising a crank in said crank chamber; an automatic air inlet valve controlling the admission of air to one of said chambers; an automatic air outlet valve controlling the emission of air from the same chamber to said conduit; a discharge valve controlling the delivery of compressed air from said conduit; and, springs operatively connected with each of said valves, normally automatically maintaining the same closed; whereby, a greater pressure is required to operate said discharge valve than said outlet valve, and, two stage compression is effected.

6. In an air compressor, the combination with a casing having cylindrical air chambers at respectively opposite ends thereof, a crank chamber between said air chambers, a conduit connecting said air chambers, and a discharge outlet from said conduit; of a piston mounted to reciprocate in said casing and alternately compress the air in said chambers; means arranged to reciprocate said piston comprising a crank in said crank chamber; an air inlet valve control-

ling the admission of air to one of said chambers; an air outlet valve controlling the emission of air from the same chamber to said conduit; a discharge valve controlling the delivery of compressed air from said conduit; and, means normally maintaining said valves closed; whereby, said discharge valve is opened at a greater pressure than said outlet valve, and, two stage 10 compression is effected.

7. In an air compressor, the combination with a casing having air chambers at respectively opposite ends thereof, a conduit connecting said air chambers, and a discharge outlet from said conduit, of a piston mounted to reciprocate in said casing and alternately compress the air in said chambers; means arranged to reciprocate said piston; an air inlet valve controlling the admission 20 of air to one of said chambers; an air outlet valve controlling the emission of air from the same chamber to said conduit; a discharge valve controlling the delivery of compressed air from said conduit; and, 25 means normally maintaining said valves closed; whereby, said discharge valve is opened at a greater pressure than said outlet valve, and, two stage compression is effected.

8. In an air compressor, the combination with a casing having cylindrical air chambers at respectively opposite ends thereof, a crank chamber between said air chambers, a conduit connecting said air chambers, and a discharge outlet from said conduit; of a cylindrical piston plunger of uniform diameter throughout its length, mounted to reciprocate in said casing and alternately compress the air in said chambers; means arranged to reciprocate said plunger comprising a cylindrical slide block mounted to reciprocate in said plunger transversely with respect to the plunger axis, a crank shaft extending transversely with respect to said 40 plunger axis, and a crank on said shaft fitted in said slide block in said crank chamber; an automatic air inlet valve opening inward and controlling the admission of air to one of said chambers; an automatic air outlet 45 valve opening outward and controlling the emission of air from the same chamber to said conduit; an automatic safety vent valve in concentric relation with said outlet valve controlling the escape of air from said conduit to the atmosphere; and, springs operatively connected with each of said valves, normally maintaining the 50 same closed; whereby, a greater pressure is required to operate said vent valve than any of the other 55 valves.

9. In an air compressor, the combination with a casing having cylindrical air chambers at respectively opposite ends thereof, a crank chamber between said air chambers, a conduit connecting said air chambers, and a discharge outlet from said conduit; of a cylindrical piston plunger of uniform diameter throughout its length, mounted to reciprocate in said casing and alternately compress the air in said chambers; means arranged to reciprocate said plunger comprising a cylindrical slide block mounted to reciprocate in said plunger transversely with respect to the plunger axis, a crank shaft extending transversely with respect to said plunger axis, and a crank on said shaft fitted in said slide block in said crank chamber; an automatic air inlet valve opening inward and controlling the admission of air to one of said chambers; an automatic air outlet valve opening outward and controlling the emission of air from the same chamber to said conduit; and, springs operatively connected with each of said valves, normally maintaining the same closed.

10. In an air compressor, the combination with a casing having cylindrical air chambers at respectively opposite ends thereof, a crank chamber between said air chambers, a conduit connecting said air chambers, and a discharge outlet from said conduit; of a cylindrical piston plunger of uniform diameter throughout its length, mounted to reciprocate in said casing and alternately compress the air in said chambers; means arranged to reciprocate said plunger comprising a cylindrical slide block mounted to reciprocate in said plunger transversely with respect to the plunger axis, a crank shaft extending transversely with respect to said plunger axis, and a crank on said shaft fitted in said slide block in said crank chamber; an automatic air inlet valve opening inward and controlling the admission of air to one of said chambers; an automatic air outlet valve opening outward and controlling the emission of air from the same chamber to said conduit; an automatic safety vent valve controlling the escape of air from said conduit to the atmosphere; and, springs operatively connected with each of said valves, normally maintaining the same closed; whereby, a greater pressure is required to operate said vent valve than any of the other valves.

11. In an air compressor, the combination with a casing having cylindrical air chambers at respectively opposite ends thereof, a crank chamber between said air chambers, a conduit connecting said air chambers, and a discharge outlet from said conduit; of a cylindrical piston plunger of uniform diameter throughout its length, mounted to reciprocate in said casing and alternately compress the air in said chambers; means arranged to reciprocate said plunger comprising a cylindrical slide block mounted to reciprocate in said plunger transversely with respect to the plunger axis, a crank shaft extending transversely with respect to said plunger axis, and a crank on said shaft fitted in said slide block in said crank chamber; an automatic air inlet valve opening inward and controlling the admission of air to one of said chambers; an automatic air outlet valve opening outward and controlling the emission of air from the same chamber to said conduit; and, springs operatively connected with each of said valves, normally maintaining the same closed.

In testimony whereof, I have hereunto signed my name at New York city, N. Y., this twenty-second day of June, 1909.

WILLIAM REAVELL.
